UNITED STATES PATENT OFFICE

FRANK F. WRIGHT, OF AURORA, ILLINOIS

METAL-SHEARING ATTACHMENT

Application filed October 7, 1927. Serial No. 224,723.

My invention relates to an improved shearing attachment particularly adapted for use with metal bending brakes and analogous machines.

5 It is an object of the invention to provide a shearing attachment which is readily and conveniently moved into and out of operative position and which will not interfere with the normal functioning of the machine to which 10 it is attached.

A further object of the invention is to provide a device of the above mentioned character which is simple and durable in construction, reliable and efficient in operation and 15 inexpensive to manufacture.

Other objects and advantages of the invention will be apparent during the course of the following description.

In the accompanying drawing forming a 20 part of this specification and in which like numerals are employed to designate like parts throughout the same,

Fig. 1, is a fragmentary front elevation of my improved shearing attachment,

25 Fig. 2, is a top plan view of the same, and,

Fig. 3, is a cross section taken on lines 3—3 of Fig. 2.

Referring to the drawing, wherein for the 30 purpose of illustration I have shown a preferred embodiment of my invention, the numeral 5, denotes one of the track supporting arms pivoted at one end to the bracket 6, as at 7. The track 8 is connected at its end to the plate 9 cast integral with the free end of arm 5, by bolts 10, it being understood that the opposite end of the track is supported by a like arm and bracket, not shown. The brackets 6 are adapted to be connected to the upper end of the standards of a conventional type of metal bending brake, or analogous machine, not shown, so when the track is in use it will be disposed on a horizontal plane above the working edge of the bending brake. To maintain the track firmly in an operative position clamping lugs 11 are pivotally mounted on the brackets 6, by wing screws 12, adapted to engage and hold down the arms 5. Thus, it is seen the track is so mounted, it may be readily and conveniently 45 swung upwardly out of the way when the ma-

chine to which it is attached is used for bending metal.

The shearing mechanism is of the traveling rotary cutter type such as disclosed in Patent Number 931,220, being mounted in a carriage 55 13, slidably mounted on the track 8. The shear carriage is drawn longitudinally of the track by a flexible metal band 14, connected thereto at 15, and having its opposite end connected to a drum inclosed in the housing 16, attached to the outermost end of the frame 17 which extends beyond the end of the track. A crank 18 actuates the drum to wind the band thereon, drawing the shear carriage 60 through the material to be cut. The inner end of the frame has a pair of vertically spaced angularly projecting ears 19 and 20, disposed in overlapping relation with respect to the ears 21 and 22, extending laterally from the depending post 23, cast integral with one 65 of the arms 5, to which they are pivotally connected by pins 24. A platform 25 adapted to receive the shear carriage upon completion of the cutting operation, extends laterally from the frame being disposed on a horizontal plane with the underside of the carriage 13, and a side plate 26 is attached to its outer edge by screws 27.

In order to maintain the frame in proper alignment with the track a catch pin 28 has 70 its ends respectively mounted in the lug 29 integral with the bottom of the drum housing 16, and the lug 30 disposed adjacent the ear 21, the latter being provided with spaced 75 openings 31, adapted to receive the end of the catch pin locking the frame in position. A spring 32 is mounted on the catch pin between the lug 29 and cotter pin 33, extending 80 through the catch pin, to normally hold the catch pin in engagement with the openings 31. The free end of the catch pin is bent 85 to provide a hand grip 34, for releasing the pin. When the shear carriage is drawn onto the platform and the catch pin released, the frame can be swung around to assume a position parallel to the track, in which position 90 it is held by the catch pin.

In operation, the shearing attachment assumes the position illustrated in Fig. 1 and 95 the metal sheet to be cut is inserted in the 100

bending brake, so that its edge is in the path of the shear carriage. The operator then draws the shear carriage across the sheet by means of the crank which winds the flexible band on the drum. When the cutting operation is completed the shear carriage is pulled onto the platform of the frame, the catch pin released, and the frame swung around to a position parallel with the track, in which position it is locked by the catch pin. The shearing attachment can then be raised upwardly above the bending brake, so as to be out of the way until its use is desired again.

It is to be understood that the form of my invention herewith shown and described is to be taken as a preferred example of the same and that certain changes in the shape, size and arrangement of the parts may be made without departing from the spirit of the invention or the scope of the subjoined claims:

Having thus described my invention, I claim:

1. In a shearing attachment of the character described, a pivotally mounted track, a shear carriage slideable on said track, means at one end of said track to receive said carriage and means for drawing said carriage along said track.

2. In a shearing attachment of the character described, a pivotally mounted track, a shear carriage slideable on said track, a pivotally mounted frame at one end of said track having a platform to receive said carriage and means for drawing said carriage along said track.

3. In a shearing attachment of the character described, a pivotally mounted track, a shear carriage slideable on said track, a pivotally mounted frame at one end of said track having a platform to receive said carriage and means carried by said frame for drawing said carriage along said track.

4. In a shearing attachment of the character described, a pivotally mounted track, a shear carriage slideable on said track, a pivotally mounted frame at one end of said track having a platform to receive said carriage, means for holding said frame in alinement with said track and means for drawing said carriage along said track.

5. In a shearing attachment of the character described, a pivotally mounted track, a shear carriage slideable on said track, a vertically pivoted frame at one end of said track having a platform adapted to receive said carriage and means carried by said frame for drawing said carriage along said track.

6. In a shearing attachment of the character described, a pivotally mounted track, a shear carriage slideable on said track, a vertically pivoted frame at one end of said track, capable of swinging to a position parallel to said track, means carried by said frame for

drawing said carriage along said track and means for locking said frame in position.

7. In a shearing attachment of the character described, a pivotally mounted track, clamps for holding said track in operative position, a shear carriage slideable on said track, a vertically pivoted frame at one end of said track, capable of swinging to a position parallel to said track, means carried by said frame for drawing said carriage along said track and means for locking said frame in position.

8. In a shearing attachment of the character described, brackets, a track, arms pivotally connecting said track with said brackets, a shear carriage slideable on said track, a vertically pivoted frame connected to one of said arms having a platform, adapted to receive said shear carriage, and means carried by said frame for drawing said carriage along said track.

9. In a shearing attachment of the character described, brackets, a track, arms pivotally connecting said track with said brackets, clamps carried by said brackets for engagement with said arms, a shear carriage slideable on said track, a frame pivotally connected to one of said arms and extending in alinement with said track having a platform, adapted to receive said shear carriage, said frame being capable of swinging to a position parallel with said track, means carried by said frame for drawing said shear carriage along said track, and releasable means for locking said frame in and out of operative position.

In testimony whereof I affix my signature.
FRANK F. WRIGHT.
